A. H. DAEHLER.

MOTOR CONTROLLING MECHANISM FOR SELF PROPELLED VEHICLES.
APPLICATION FILED AUG. 30, 1907.

1,020,889.

Patented Mar. 19, 1912.

UNITED STATES PATENT OFFICE.

ALFRED H. DAEHLER, OF LOS ANGELES, CALIFORNIA.

MOTOR-CONTROLLING MECHANISM FOR SELF-PROPELLED VEHICLES.

1,020,889.

Specification of Letters Patent. Patented Mar. 19, 1912.

Application filed August 30, 1907. Serial No. 390,805.

To all whom it may concern:

Be it known that I, ALFRED H. DAEHLER, a citizen of the United States, residing at Los Angeles, in the county of Los Angeles and State of California, have invented new and useful Improvements in Motor-Controlling Mechanism for Self-Propelled Vehicles, of which the following is a specification.

This invention relates to improvements in mechanism for controlling the prime mover in automobiles.

The primary object of this invention is to combine in a single mechanical device, the throttle and spark-controlling elements of a gas engine.

Another object is to provide a device in which the control of the throttle and spark is facilitated, and the necessary employment of two or more levers for separately operating the throttle and timing the spark, is dispensed with.

A further object of my invention is to eliminate the supporting or stationary tube usually employed to prevent rotation of the spark and throttle regulating levers with the hand wheel; without said tube the levers would ordinarily rotate with the hand wheel.

This invention consists of such further features, details of construction and combination of parts as will be described in connection with the accompanying drawing and then be more specifically pointed out in the claims.

In the drawings: Figure 1 is a fragmentary sectional elevation of a steering wheel and tube of an automobile, showing the invention as applied. Fig. 2 is a fragmentary plan view partly in section, on line 2—2 of Fig. 1, of the steering wheel, showing the controlling lever for operating the spark and throttle. Fig. 3 is an enlarged transverse section on line 3—3 of Fig. 1, and Fig. 4 is a perspective of the disjoined lower portion of the controlling mechanism, showing the construction thereof.

Referring more in detail to the drawing, 1 designates an automobile steering wheel secured onto the end of a hollow rod 2 to which the steering mechanism for the wheels of the vehicle is attached.

3 is a two part housing for the worm 4 provided on the rod and the sector 5 which is in constant mesh with said worm 4, and through which movement is imparted to the steering arm 6, made integral with the sector 5. This housing 3 has bolted to the

under side thereof a plate 7 which in conjunction with the housing forms a rest for the steering and controlling mechanism. A hollow boss 8 is integrally united with said plate 7 and is cut away at the lower portion thereof to accommodate a sleeve 9 onto which is rigidly secured a spark regulating lever 10. A collar 11 is secured on said boss by a set screw 12, to hold said sleeve in place. The sleeve 9 is provided with a diagonal slot 13. A lug 14 provided on the lower end of a hollow tube 15 which extends through the bore of the hollow rod 2, is arranged to project into the vertical slot 8', to prevent rotation of the tube 15, and an extension 14' of said lug engages the diagonal slot 13 in said sleeve and by a vertically reciprocating movement thereof, to impart a rotary motion to said sleeve 9, thereby to control the spark-regulating lever 10 of the engine. Contiguous with said boss 8 and below said collar 11, is a recessed portion 16, provided with an orifice 17 for the reception of the reduced terminus 18 of the stem 19, which extends through the bore of the hollow tube 15. The bottom of this recessed portion 16 forms a bearing surface for the shoulder 20 provided on the end of the stem 19.

21 is a controlling lever fixedly attached to the stem 19 for controlling the throttle.

The hollow tube 15 extending through the hollow rod 2 has secured to it a short sleeve 22, terminating at a point slightly above the level of the steering wheel 1 in a sphere 23, half of which is integral with the sleeve 22 and the other half of which is formed by a cap 24 provided with a hemispherical concavity. The cap 24 is secured to the sleeve 22 by bolts and nuts or set screws 25 which extend through the lips 26 made integral with the cap 24 and the sleeve 22.

27 designates grooved guide-ways provided in the sections of the sphere 23, said guide-ways being arranged to accommodate an apertured ball 28, through which a governing arm 29 extends. The ball 28 revolves and travels in the circular grooves, as the arm 29 is given a radial motion by the operator of the machine. Said arm has integral therewith a disk provided with a ratchet face 30 which is arranged to be always held in engagement with a similar ratchet face 31 provided on the stem 19, by a helical spring 32 coiled about the shank of the stud 33 which pivotally secures the

stem and the governing arm together. A collar 34 is fixed on the end of the stud 33 to prevent the displacement of the spring.

35 is a nut screwed on to the threaded end 5 of the stud and 36 is a lock nut also screwed on the stud. The object of this provision is to secure the operating lever in any position of vertical adjustment, the helical spring tending to normally hold the ratchet faces 10 in mutual engagement, and to permit of a most limited movement of the lever, governable solely by the distance intermediate the ratchet teeth. Thus the advance or retarding of the spark is constantly under the 15 positive and perfect control by the operator of the machine. By this construction it will be seen that the spark timer controlling lever is operated by the vertical movement of the hollow tube without disturbing the determined 20 position of the throttle controlling lever, and likewise the latter is controllable by a circular movement of the governing arm 29 without moving or dislocating the spark timing lever 10 from any predetermined 25 position.

The term "compensating means" has reference to the ball 28 which is located in the grooves, and through which the governing arm extends, whereby the relative variation 30 of the travel of the governing arm and sphere is in a measure balanced. The term has been employed for want of a better.

Having described my invention, what I claim is:

35 1. The combination with a hollow steering rod and a steering wheel, of a hollow tube extending through said rod, a lug on said tube, a seat for said lug to prevent the rotation of said tube, a sleeve provided with 40 a diagonal slot, said lug being arranged to extend in the pathway of said slot, a spark-timer controlling lever on said sleeve, a stem extending through said tube, a throttle regulating lever on said stem, and means 45 for operating said tube and stem simultaneously or independently of each other.

2. The combination with a hollow steering rod, and a steering wheel; a spark timing controlling tube; a stem in said tube; a 50 throttle regulating lever on said stem; a governing arm pivotally attached to said

stem and provided with an apertured ball; a spherical body inclosing the pivotal joint of said arm and stem, said body being provided with a circular guide way to accommodate said ball, and means whereby a vertically reciprocating movement of said arm imparts a rotary motion to said spark timing lever, and a circular movement of said arm imparts a rotary motion to said stem 60 and throttle regulating lever.

3. A tube, a lug on said tube to prevent rotation thereof, a motor controlling element, having a slot to accommodate said lug, a motor controlling stem extending 65 through said tube, and a single lever having a reciprocatory movement to rotate said element and an oscillatory movement to oscillate said stem.

4. The combination with a hollow steering rod and a hand wheel secured thereto, of a tube extending through said rod, a lug on said tube, a motor controlling element operatively connected with and rotatable by the vertical movement of said lug, a stem 70 extending through said tube, another motor controlling element connected with said stem, and a lever connected with said stem to oscillate the same, said tube being also operatively connected with said lever to reciprocate said tube.

5. The combination with a hollow steering rod and a steering wheel secured thereto, of a tube extending through said rod and provided with a lug, means engaging said lug to hold said tube against rotation, a motor controlling connection operatively connected with said lug, a stem extending through said tube, another motor controlling element connected with said stem, and a lever pivotally connected with said stem to rotate the same, said tube being also operatively connected with said lever and movable in but one direction therewith.

In testimony whereof, I affix my signature, in presence of two subscribing witnesses.

ALFRED H. DAEHLER.
